ABSTRACT

A gyratory crusher provided with a wobbling crusher cone supported by a dish-shaped sliding bearing on the upper end of an axially slidable piston arranged in a stationary tubular shaft and provided at the lower end of the piston with a pressure medium chamber for adjusting the piston slidably in said tubular shaft is provided with a lubricant system comprising a lubricating channel extending centrally along the axis of the entire piston and connected with its upper end with the center of said sliding bearing, while the lower end of said lubricating channel slidably engages a tubular pin which extends through said pressure medium chamber and is fixedly attached to a cover plate which closes the lower end of said tubular shaft. An exterior lubricant supply source is connected with the lower end of said tubular pin which extends through said cover plate.

LUBRICANT FEED MEANS FOR GYRATORY CRUSHERS

The invention relates to a gyratory crusher provided with a wobbling crusher cone supported by a vertically movable dish-shaped sliding bearing mounted on the upper end of an axially adjustable piston.

In known gyratory crushers of this type the piston is slidably supported in a stationary tubular shaft which is fixedly attached to the housing of the gyratory crusher. The piston is hydraulically or pneumatically vertically adjustable, but it is not rotatable. Furthermore, there is provided between the lower end of the piston and the housing of the gyratory crusher a cylindrical space which is charged with a suitable pressure medium, such as a pressure fluid or a gas under pressure, for the purpose of adjusting the piston slidably in the tubular shaft.

At the upper end of the piston is arranged in most cases a spherical segment serving as the supporting dish of the sliding bearing. On this spherical segment is mounted the crusher cone which by means of an eccentric sleeve, which surrounds the tubular shaft, is rotated by driving gears so that the crusher cone performs in the crusher space a wobbling movement.

A gyratory crusher of this type is disclosed in the U.S. Pat. No. 3,372,881 and in this known crusher the lubricant for the lubrication of the sliding bearing is supplied by a channel arranged in the housing of the gyratory crusher in such a manner that it avoids the space which contains the pressure medium for adjusting the piston. This channel in the housing of the gyratory crusher is in communication with an annular chamber which surrounds the axially slideable piston, so that the lubricant is pumped through this channel into the mentioned annular chamber. This annular chamber is in communication with a lubricating channel in the piston which leads directly to a central distribution chamber in the sliding bearing. This known arrangement of a lubricating system for a gyratory crusher requires, however, relatively large sealing devices, particularly around the annular chamber and in the housing and in the neighborhood of the bearing for the piston.

These sealing devices have relatively large sealing surfaces and an inner diameter which depends on the exterior dimensions of the piston. Owing to the axial adjustability of the piston these sealing devices wear very quickly and lubricant leaks are apt to appear at the annular chamber and this in turn leads to an insufficient lubrication of the highly stressed bearing of the crusher cone and causes damage to this bearing. An exchange and replacement of a sealing device which has become worn at the annular chamber is, however, very difficult to accomplish.

An object of the present invention is to provide a gyratory crusher with a lubricating feed means which in its dimensions is independent of the diameter of the piston and which without expensive installation operations can easily be applied to the gyratory crusher.

In accordance with the invention, the lubricating channel in the piston is arranged in axial direction along the entire length of the piston and is connected with a tubular pin which is fixedly attached to the housing of the gyratory crusher and also is slidably and sealingly connected with the lubricant channel in the piston. This tubular pin extends entirely through the cylindrical chamber provided at the lower end of the piston and which is charged with a pressure medium for ad-

justing the piston lengthwise. This tubular pin can very easily be sealingly connected with the lubricating channel of the piston by providing the lower end of the lubricating channel with a cylindrical enlargement which in its walls is provided with sealing rings which slidably engage the upper end of the tubular pin, the other end of which is fixedly attached to a cover plate which closes the lower end of the tubular shaft which in turn is fixedly attached to the housing of the gyratory crusher. Preferably the tubular pin is threadedly attached to the mentioned cover plate or may also be welded or soldered thereto. In the embodiment of the invention illustrated, for example, in the accompanying drawing a threaded connection establishes a tight connection between the tubular pin and the cover plate in very simple manner, whereby at the same time a good seal is obtained. Preferably the hollow cylindrical enlargement in the lower portion of the piston and the cylindrical chamber below the piston are arranged in axial alignment so that the piston can be longitudinally adjusted without any difficulties.

For the purpose of describing the lubricating system of the invention more clearly, the accompanying drawing illustrates such a lubricating system arranged in a gyratory crusher.

In the drawings:

FIG. 1 illustrates a vertical longitudinal section of a gyratory crusher; and

FIG. 2 illustrates an enlargement of the lower portion of this gyratory crusher.

Referring to FIG. 1 the stationary portion of the gyratory crusher comprises an upper portion 1 provided with a filling aperture 2, a crushing tool 3 and the housing 4. A hollow conical crusher cone 5 is mounted directly on a hollow supporting cone 6 in the interior of which is arranged a spherical segment 7 resting on a supporting dish 8 of the sliding bearing. The transverse stresses acting on the crusher cone 5 are taken up by a cylindrical bearing surface 9 on which revolves an eccentric sleeve 11 driven by bevel gears 10 mounted with their driving shaft in the housing. The eccentric sleeve 11 is rotatably mounted on the tubular shaft 12 which is fixedly secured with its lower end to the housing 4 of the gyratory crusher. The supporting dish 8 of the sliding bearing is mounted on the upper end of a piston 13.

This piston 13 is axially slidably arranged in the tubular shaft 12 and is provided with a pre-tensioned spring 14 acting as a safety element against overloading of the crusher cone 5. The spring 14 comprises a stack of individual annular springs. This spring 14 is arranged between the upper part 13a of the piston 13 and the lower part 13b thereof and is mounted on a guide rod which is not illustrated in the drawing. The lower part 13b of the piston 13 extends into a cylindrical chamber 15 which is filled with a pressure medium supplied by a control device. This pressure medium, for instance a pressure fluid, when pumped into the space 15 effects a vertical adjustment of the piston 13 and thereby accomplishes an adjustment of the size of the crusher gap 16.

For the lubrication of the sliding bearing comprising the parts 7 and 8, the piston 13 is provided with a central bore 17 which establishes a communication with a lubricating channel 18 in the lower part 13b of the piston 13. This channel 18 also extends axially through the abovementioned guide rod for the spring 14. The lower

part 13b of the piston is slidably connected with a tubular pin 19 which extends entirely axially through the cylindrical chamber 15 of the hydraulic control device. The pin 19 extends slidably into a hollow cylindrical enlargement 20 in the lower part 13b of the piston. The lower or outer end of the pin 19 which extends outwardly of the housing is connected with a lubricant supply line 22.

FIG. 2 illustrates in an enlarged scale the lower part of the gyratory crusher.

In this embodiment of the invention the outer surface of the tubular shaft 12 is shaped slightly conical. A nut 23 is applied to its lower end and clamps the tubular shaft 12 securely in a suitable seat in the housing 4 of the gyratory crusher. The lower part 13b of the piston 13 extends into a sleeve 24, the lower end of which forms the chamber 15 for the pressure medium. The pressure medium, for instance oil, is supplied or withdrawn by a pipe 25. The pressure medium serves for the adjustment of the gap 16 of the gyratory crusher.

Referring particularly to FIG. 2, it should be noted that the tubular pin 19 for feeding the lubricant into the cylindrical enlargement 20 of the channel 18 is threadedly connected with the closure plate 26 which closes the lower end of the tubular shaft 12. A hexagonal nut 27 urges a sealing washer 27a against the lower face of the closure plate 26. The tubular pin 19 is provided with a passage extending entirely lengthwise and axially through the pin 19. The lower or outwardly extending end of the pin 19 is provided with a coupling sleeve 21 which in turn is connected with a lubricant supply line 22. The upper end 28 of the tubular pin 19 has a reduced diameter and slidably engages the hollow-cylindrical enlargement 20 arranged in the lower part 13b of the piston 13.

The hollow cylindrical enlargement 20 is preferably arranged in axial alignment with the central channel 18 in the piston 13. The wall of this hollow cylindrical enlargement 20 is provided with annular grooves in which sealing rings 29 are inserted which engage the circumference of the reduced upper portion 28 of the tubular pin 19.

The lubricant channel 18 may be connected with separate channels which are used for directing the lubricant to additional bearings provided in the gyratory crusher. In particular, an additional channel may be directed to the arrangement of the annular springs used to cushion an overload to which the crushing cone may be subjected in order to lubricate this spring arrangement.

ment.

The illustrated construction of the lubricating system of the invention may be modified in that, for instance, the tubular pin 19 is rigidly connected with the piston 13. In such a case the lower end of the tubular pin 19 passes slidably through a suitable passage in the wall of the housing 4, for instance, in the cover plate 26 which closes the lower end of the tubular shaft 12. Advantageously, the sealing devices to be used in this case may comprise annular grooves arranged in the wall of the bore in the housing 4 through which the tubular pin 19 extends outwardly. The sealing rings are then easily accessible.

What we claim is:

1. A gyratory crusher, comprising
  - a. a housing having a feed opening at the top thereof,
  - b. a crusher lining secured to said housing adjacent said top opening therein,
  - c. a tubular support post stationarily mounted in an upright position within said housing and having a closed bottom end,
  - d. a piston mounted in said tubular support post for movement axially thereof,
  - e. a rotary crusher cone mounted on the upper end of said piston,
  - f. a substantially dish-shaped friction bearing between said crusher cone and said upper end of the piston,
  - g. eccentric means associated with said rotary crusher cone and support post to impart to said crusher cone a wobbling movement,
  - h. means for supplying highly pressurized fluid to the variable size chamber formed by the bottom end of said piston and said closed bottom end portion of the support post to thereby control the size of the gap between the crusher lining and the crusher cone,
  - i. a conduit extending axially through said piston from said friction bearing to the bottom end of the piston,
  - j. a tubular member secured to the bottom closure of said support post and extending through said closure into said conduit in the piston in sealed slidably engagement with the wall of said conduit, and
  - k. means for supplying low pressure lubrication fluid to the outer end of said tubular member and thereby to said friction bearing.
